UNITED STATES PATENT OFFICE

90,821

DESIGN FOR A CONTAINER

Lowell J. Smith, Connersville, Ind.

Application April 3, 1933. Serial No. 47,674

Term of patent 7 years

To all whom it may concern:

Be it known that LOWELL J. SMITH, a citizen of the United States, residing at Connersville, in the county of Fayette and State of Indiana, has invented a new, original, and ornamental Design for a Container, of which the following is a specification, reference being had therein to the accompanying drawing, forming part thereof.

The figure is a side elevation of a container, showing my new design.

I claim:

The ornamental design for a container, as shown.

LOWELL J. SMITH.
